SAFETY VALVE DEVICE

Eugene Paillé, Los Angeles, Calif., assignor to
Thermac Company, Los Angeles, Calif., a cor-
poration of California

Application July 7, 1947, Serial No. 759,397

5 Claims. (Cl. 137—66)

1

This invention relates to a safety valve device, and particularly to such devices that are employed for controlling the flow of a fuel such as gas, to a main burner, and to a pilot burner. The type of valve device to which my invention relates, usually includes a rotary plug valve, or plug cock, which permits the flow of gas to the main burner when in its open position, and the construction usually provides a pilot port which operates independently of the rotary valve, to supply the fuel at all times when the device is in operation, to the pilot burner. These devices also frequently include a valve closure which, when it is open, maintains a continuous supply to the pilot burner. Under normal conditions, if the main burner has not been lighted, the rotary valve will be standing in its "off" position, that is to say, it will be closing off flow of fuel to the main burner, although the other valve, that is to say, the valve closure, will be in its open position supplying fuel to the pilot burner.

The valve parts referred to above, usually operate in conjunction with a thermo-electric couple, or thermo-electric pile, which is located in the vicinity of the pilot burner, and which is normally maintained heated by the pilot flame so as to maintain sufficient current flow in the coils of an electromagnet to enable it to maintain an armature connected with the valve closure, in a position close to the electromagnet, thereby holding the valve closure in its open position.

With apparatus such as described, it may happen that for some reason or other, for example, from a strong wind, or from a sudden accidental failure in the normal gas pressure, the pilot burner may become extinguished. When this happens, of course the current in the electromagnet fails, and the spring which is usually associated with the valve closure, will move this valve to its closed position, thereby shutting off all flow of gas to the main burner and pilot burner, regardless of the position of the rotary valve referred to. When this occurs, it becomes necessary to reset the valve closure in its open position, which involves re-lighting the pilot burner, at the same time, holding the valve closure open long enough to permit the thermocouple to energize the coils of the electromagnet sufficiently to enable it to hold the armature close to it, which will of course hold the valve closure in its open position. Of course the rotary valve should be in its "off" position, or closed position, when the pilot burner is lighted. However, these devices are frequently operated by persons who are not familiar with such apparatus, and such a person may not even observe that a pilot burner has become extinguished, and may attempt to light the pilot burner while gas is being supplied to the main burner. Applying a match to the pilot burner under these circumstances would immediately light all the

gas that has been passing through to the main burner, and such a procedure in lighting such a burner is dangerous.

In other words, the setting of this apparatus into its proper relation to function as it should, involves a certain procedure which should insure that the pilot burner is ignited a considerable time before the fuel can be turned in a considerable volume into the main burner.

10 One of the objects of this invention is to provide a safety valve device of this kind, which is of simple construction, and which is so constructed that it is impossible for the operator of the device to set or re-set the apparatus and ignite the pilot burner while the rotary valve referred to is in its open position, and supplying gas or fuel in quantity to the main burner.

Another object of the invention is to provide such a device with a hand-operated member, or handle, which cooperates with the other parts of the device in an organization of parts which will enable this handle or means associated with the handle, to perform the function of rotating the rotary valve, and also manually opening the valve closure; at the same time, organizing the parts in such a way that the movement of the handle member that effects the opening of the valve closure, can not be performed unless the rotary valve is in its "off" position, at which time it will not be supplying any fuel to the main burner.

Another object of the invention is to provide correlated means associated with the casing of the valve device, and the operating handle referred to above, which will indicate to the operator of the device, the position that the rotary valve is in; and which will cooperate to prevent a shifting movement of the handle along its own axis unless the rotary valve is in its "off" position.

40 In the preferred embodiment of this invention, the rotary valve is in the form of a tapered plug which is received in a tapered socket or seat in the casing; and the operating handle for rotating this tapered plug, is mounted in the casing so that it is capable of being shifted along its own axis to effect the opening of the valve closure; and one of the objects of this invention is to provide improved means for effecting the connection between the handle member and the rotary valve, or plug, capable of not only rotating the plug, but capable of moving longitudinally along its own axis to effect the opening of the valve closure; and including a single resilient means or spring, which urges the plug in a direction to maintain it properly tight in its seat, and at the same time, to maintain the operating handle in its normal outward or elevated position from which it can be pushed inwardly when the rotary valve is in its closed position.

Further objects of the invention will appear hereinafter.

The invention consists in the novel parts and combinations of parts to be described hereinafter, all of which contribute to produce an efficient safety valve device.

A preferred embodiment of the invention is described in the following specification, while the broad scope of the invention is pointed out in the appended claims.

In the drawing:

Fig. 1 is a vertical section through a valve device embodying my invention, certain parts being broken away and shown in elevation, and others in partial section. In this view the electromagnet that cooperates with the armature of the device, is also illustrated, together with the pilot burner, which is supplied with fuel from the pilot port of the valve device.

Fig. 2 is a horizontal section taken about on the line 2—2 of Fig. 1, further illustrating the correlated means for connecting the handle member and the casing to prevent a wrong operation of the device, and also illustrating the preferred character of the connection between the handle member and the rotary valve, that enables the rotary valve to be rotated at will, at the same time permitting the shifting movement of the handle that opens the valve closure if the rotary valve is in its closed position.

Referring more particularly to the parts, the apparatus illustrated includes a casing 1, which has a tapered bore 2 in which is mounted the rotary valve closure or plug 3, which plug has a peripheral conical wall as shown, and is open at its small end where the chamber or passage 4 within it, emerges at the lower end of the tapered bore 2 where a small chamber 5 is formed between the lower end of this plug and a main valve closure 6. The peripheral wall of the plug is provided with a side port 7 that is illustrated as being in alignment with a passage or port 8 in the casing, which supplies fuel to a main burner, not illustrated. On the opposite side of the valve casing as illustrated, a fuel inlet 9 is placed, which admits the fuel into a valve chamber 10 located below the valve closure 6. In other words, the valve closure 6 is in the line of flow of the fuel from the inlet to the outlet 8, and when it is in its closed position on its valve seat 11, it completely closes off flow of the fuel through the outlet 8 to the main burner, and also through a pilot port 12 which can supply fuel to a pilot burner 13.

Operatively connected with the valve closure 6 so as to move in unison with it, an armature 14 is provided, which cooperates with an electromagnet 15, the coils, or coil 16 of which is supplied with electric current from a thermocouple 17, the upper end of which is in proximity to the flame at the upper end of the pilot burner, which flame, or flames, are indicated by the dotted lines 18.

Suitable means is provided for biasing the valve closure 6 to, or toward, its closed position. In the present instance, this means is illustrated as consisting of a coil spring 19, the upper end of which thrusts against the under side of the valve closure, and the lower end of which thrusts against a disc or head 20 attached to the lower side of the casing 1, so as to operate as a closure for the under side of the valve chamber 10.

The armature 14 and the electromagnet 15 may be housed in a small cup-shaped sub-casing 21, which carries terminals such as the terminal 22 to which the conductors of the electric cord 23

are attached, which cord is attached to the lower end of the thermocouple 17. Conductors 24 and 25 within the sub-casing 21, are connected to the coils 16.

5 In applying my invention to a valve construction such as described, I mount the main valve closure 6 rigidly on the inner end of a valve stem 26, and guide it below through a guide opening centrally located in the head 20, below which the 10 stem may be provided with a ball head 27, which is socketed in the upper side of the armature 14. The mouth of this socket can be peened over slightly to retain the armature on the ball.

The stem 26 extends up through the upper end 15 of the plug 3, so that the stem 26 presents a projecting portion 26a that extends upwardly beyond the upper end of the plug. At this point a coupling member 28 is provided, which can be rotated by a handle member 29 on the exterior of the casing, and the connection between this coupling 28 and the plug 3 is such as to permit the coupling to rotate the plug; and this connection also permits the coupling 28 to be shifted along the axis of the plug. In order to accomplish 20 this, the upper end of the plug is formed into an upwardly extending neck 30, which has flat side faces 31; the coupling 28 is made originally of cylindrical form, and is then broached out at its middle portion and transversely to divide it 25 into two forks 32, which forks have flat faces 33 to fit against the flat side faces 31 of the neck 30. The coupling 28 is either attached to a spindle, or is made with an integral extension as illustrated, forming a spindle 34, the upper end of 30 which has a square shank 35 that is socketed in a similarly shaped socket in the lower end of the shank 36 that forms a part of the knob or handle member 29. This shank 36 may be rigidly secured to the spindle 34.

Between the upper end of the plug 3 and the lower end of the coupling 28, a coil spring 37 is provided, which performs the double function of pressing the tapered plug 3 downwardly into its conical seat, and also holding the coupling 28 in its extreme elevated position, at which time its upper end is held against the under side of a screw cap 38 that is screwed onto the threaded upper end of the casing 1.

The spindle 34 and the casing cap 38 are provided with correlated means which will prevent the handle member 29 and its shank 35 from being pushed downwardly if the valve plug 3 is in its open position as shown in Fig. 1. To accomplish this I provide a stop surface on the valve casing adjacent to a stop, or stop finger that moves 55 along that surface when the rotary valve is being rotated towards its open position. This surface is formed so that it will prevent the opening of the main valve-closure until the rotary valve has been rotated into its fully closed position. For this purpose, I prefer to provide a radially disposed stop finger or pin 39 that projects outwardly from the spindle 34, and when the plug 3 is in this position, the pin 39 will rest on the dwell 40 of a cam face 41, which extends circumferentially around the spindle 34, and which forms a portion of the upper surface of a collar or sleeve 42 that may be formed integrally with the upper side of the screw cap 38. In this position the side 60 of the pin rests against a shoulder 43 that is disposed in a vertical plane as illustrated in Fig. 2.

Between the upper end of the projection 26a and the under face 44 of the coupling 28, a clearance space is provided, as shown, when the spindle

34 is in this relatively elevated position with the pin 39 resting on the dwell 40.

The mode of operation of the apparatus in resetting it from the position of the parts illustrated in Fig. 1, will now be described. In this connection, however, it should be understood that the flames indicated at 13, are supposed to be extinguished, and by reason of this supposition, the electromagnet 15 will have become de-energized, and the effective loss of its magnetic lines of force will have released the armature 14 so that the spring 19 is holding the valve closure 6 closed. In order to re-set this valve device, the handle member 29 should be pressed down against the cam face 41, which causes the handle to rotate in a clockwise direction through approximately 180°. This will rotate the stop pin 39 around to an opposite position from that in which it is illustrated in Fig. 1, at which time it will have moved far enough down along the cam surface 41 to re-set the main valve-closure. This rotation of the handle member 29 through 180° will of course swing the port 7 around and away from the port 8 of the casing with which it has been in communication. As this movement is being completed the face 44 of the coupling 28 will impinge upon the upper face of the projecting end 26a of the stem 26, and will push this stem downwardly, thereby carrying the valve closure 6 to its open position, and also bringing the armature 14 within the range of the magnetic flux of the electromagnet 15. The pilot burner 13 should then be lighted while the armature 14 is held down sufficiently long to enable the thermo-pile 17 to generate enough current to enable the electromagnet to hold the armature down. If the operator of the device then wishes to light the main burner, this can be done with perfect safety by rotating the handle 29 back to the position in which it is indicated in Fig. 1.

Many other embodiments of the invention may be resorted to without departing from the spirit of the invention.

I claim as my invention:

1. A valve for controlling flow of fuel to a burner and to co-operate with a thermo-electric pilot controlling electro-magnet, the combination of a valve casing, a rotary valve-closure within the casing capable of assuming an open position in which the fluid flows through the said casing, a main valve-closure in the path of flow of the fuel through the valve casing and capable of assuming a closed position to shut off flow of the fuel; means for biasing said main valve closure towards its closed position, a handle-member on the exterior of said casing for rotating the rotary valve-closure, a coupling member within the casing on the rotary valve closure operatively connected to the handle-member for rotation thereby, said rotary valve and said handle-member having a driving connection between them permitting longitudinal shifting of the handle member with respect to said rotary valve-closure to open the main valve-closure, said main valve-closure having a stem for moving the same to its open position, and guided to slide longitudinally in said rotary-valve closure, an armature carried by said stem to co-operate with the electromagnet, said handle-member having a part for engaging the stem during said shifting movement to open the main valve-closure; a stop-member projecting radially from the handle-member at the exterior of said casing, said casing having a circumferentially disposed stop-face adjacent the

path of said stop-member, and co-operating with the same to prevent the shifting movement of said handle-member from opening the main-valve closure unless the rotary valve closure is in its closed position.

2. A valve for controlling flow of fuel to a burner, and to co-operate with a thermo-electric pilot-controlling electro-magnet, according to claim 1, in which the coupling member within the casing includes a neck projecting toward the handle-member with a flat face substantially parallel with the axis of the rotary valve-closure; and a handle-member including a coupling member within the casing having a flat face engaging the first named flat face for enabling the rotation of the handle-member to be imparted to the rotary valve-closure; and including resilient means for normally holding the handle-member in its normal position.

3. A valve for controlling flow of fuel to a burner, and to co-operate with a thermo-electric pilot-controlling electro-magnet, according to claim 2, in which the said neck on the rotary valve includes two diametrically opposite faces both of which are substantially parallel to the axis of the rotary valve-closure; and in which the handle-member has a socket receiving the said neck with flat faces to slide on the faces of the neck during the shifting movement of the handle-member that opens the main valve-closure.

4. A valve for controlling flow of fuel to a burner, and to co-operate with a thermo-electric pilot-controlling electro-magnet according to claim 1, in which the outer wall of the said casing is formed with an abutment carrying the said circumferentially disposed face that co-operates with the said radially projecting stop-member, thereby enabling the said shifting movement of the handle-member that opens the main valve-closure to start during the rotary movement of the handle-member that is imparted to the rotary valve-closure.

5. A valve for controlling flow of fuel to a burner, and to co-operate with a thermo-electric pilot-controlling electro-magnet, according to claim 1, in which the coupling member on the rotary valve-closure includes a neck integral with the rotary valve-closure projecting toward the handle-member, said neck having a pair of oppositely disposed flat faces substantially parallel with the axis of the rotary valve-closures, and in which the handle-member includes a socket having flat faces sliding on said first named faces during the shifting movement of said handle-member that opens the main valve-closure, and in which the said stem projects upwardly beyond the end of the neck and into the path of movement of said socket during the shifting movement that opens the main valve-closure.

EUGENE PAILLE.
